PAGE 5

FIG. 9

FIG. 10

FIG. 11

FIG. 12

FIG. 1 is an isometric view of a sewage treatment plant embodying my new design and showing the front, top and right end of the plant;

FIG. 2 is a top plan view of the sewage treatment plant shown in FIG. 1. The bottom plan view of the plant is plain;

FIG. 3 is a rear elevational view of the sewage treatment plant shown in FIG. 1. The front elevational view of the plant is the same in appearance as this view;

FIG. 4 is a side elevational view of the sewage treatment plant shown in FIG. 1 as taken from the left end thereof. The right end is shown in FIG. 1;

FIG. 5 is an isometric view of a sewage treatment plant embodying a modified form of my new design, and showing the front, top and right end thereof;

FIG. 6 is a top plan view of the sewage treatment plant of FIG. 5. The bottom plan view of the plant is plain;

FIG. 7 is a rear elevational view of the sewage treatment plant of FIG. 5. The front elevational view of the plant is the same in appearance as this view;

FIG. 8 is a side elevational view of the sewage treatment plant of FIG. 5 as taken from the left end thereof. The right end is shown in FIG. 5;

FIG. 9 is an isometric view of a sewage treatment plant embodying another modified form of my new design, and showing the front, top and right end thereof;

FIG. 10 is a top plan view of the sewage treatment plant of FIG. 9. The bottom plan view of the plant is plain;

FIG. 11 is a rear elevational view of the sewage treatment plant of FIG. 9. The front elevational view of the plant is the same in appearance as this view; and,

FIG. 12 is a side elevational view of the sewage treatment plant of FIG. 9 as taken from the left end thereof. The right end is shown in FIG. 9.

I claim:

The ornamental design for a sewage treatment plant, substantially as shown and described.
